CLOSING MECHANISM FOR BOTTOM-DUMP WAGONS

George W. Mork, South Milwaukee, Wis., assignor to Bucyrus-Erie Company, South Milwaukee, Wis., a corporation of Delaware

Application February 28, 1948, Serial No. 11,985

3 Claims. (Cl. 298—35)

1

My invention relates to new and useful improvements in spreading devices for bottom-dump wagons.

Such wagons are well known, and may be of the full-trailer or semi-trailer type. In the full-trailer type, the wagon body is hung between a front truck and a rear truck. In the semi-trailer type the wagon body is hung between a goose-neck, attachable to the towing means, and a rear truck.

My invention is herein shown as applied to a wagon of the semi-trailer type, but is equally applicable to the other type.

The body usually has downwardly converging sides and ends, and its bottom is longitudinally split along the middle to form two downwardly and outwardly opening doors.

These doors are opened and closed by one or more preferably double-acting hydraulic cylinders which may be directly connected to the doors, but are more commonly indirectly connected thereto by a rope and tackle block in such a manner that action of the cylinders in one direction draws on the rope to close the doors and action of the cylinder in the other direction slackens the rope allowing the doors to open. In the past the doors have been held in closed position by the hydraulic cylinders. With such an arrangement, however, leakage in the cylinder or valve or any other part of the hydraulic circuit permits the doors to open gradually.

Accordingly it is the principal object of my invention to provide a simple means for locking the doors in position, such that:

(1) Pressure and attendant leakage in the hydraulic circuit is either greatly reduced, or entirely eliminated.

(2) No additional or independent control means is required to unlock the doors, unlocking occurring automatically upon reversal of the cylinder stroke.

(3) No additional mechanical elements are required.

In addition to my principal objects above stated, I have worked out a number of novel and useful details, which will be readily evident as the description progresses.

My invention consists in the novel parts and in the combination and arrangement thereof, which are defined in the appended claims, and of which two embodiments are exemplified in the accompanying drawings, which are hereinafter particularly described and explained.

Throughout the description, the same reference number is applied to the same member or to similar members.

Figure 1 is a side elevation of a wagon embodying my invention.

2

Figure 2 is a plan view of the same.

Figure 3 is an enlarged front-end view of the first embodiment of my hydraulic cylinder and locking mechanism, taken along the lines 3—3 of Figure 1.

Figure 4 is a plan view taken along the lines 4—4 of Figure 3.

Figure 5 is a view, similar to Figure 3, showing a second embodiment of my invention.

10 Turning now to these figures, we see that 11 is the conventional body of a bottom-dump wagon, supported at the rear by wheels 12, and at the front by goose-neck 13. It has two bottom-dump doors 14. In Figure 1, these doors are shown closed in full line, and open dotted. They open downwardly and outwardly, being pivoted longitudinally, one on each side of the bottom of the wagon body 11, as for example by hinges 37.

20 Turning to the first embodiment shown in Figures 3 and 4, we see that hydraulic cylinder 15 is pivotally mounted preferably at a front corner of the wagon, as at 16. In this embodiment, the cylinder is double-acting, and the fluid 25 to actuate it is conducted by pipes 17 which lead from the towing vehicle to the cylinder. The towing vehicle, pipes thereon, and control valves therefor are conventional, and hence are not shown.

30 Piston rod 26 of cylinder 15 is connected as at 18 to one arm 19 of a bellcrank 20 which is pivoted preferably at 21 on the other side of the wagon front. Inside the other arm 22 of bellcrank 20 is mounted as at 23 tackle block 24, 35 preferably with multiple sheaves. Another similar tackle block 25 is mounted on the other side of the wagon front, preferably at cylinder pivot 16. Tackle block 24 is thus seen to be movable and tackle block 25 fixed relative to the wagon body. When piston rod 26 is fully extended, tackle block 24 is farthest from tackle block 25, as shown in full lines in Figure 3. It should be noted that, in the full-line position, bellcrank 20 abuts the side wall of wagon-body 11, and hence cannot rotate counter-clockwise any further. Thus the part of body 11 where bellcrank 20 abuts, amounts in effect to a mechanical stop.

40 When piston rod 26 is drawn into cylinder 15, the tackle blocks 24 and 25 are nearest together, as 45 shown by dotted lines in Figure 3. Accordingly by reeving rope 27, by means of which the downwardly swinging doors 14 are suspended from the wagon body, between tackle blocks 24—25, the doors are opened or closed by actuating the 55 cylinder to move the tackle blocks respectively together or apart.

A preferred reeving of rope 27 is to have it run from anchorage 28 at the front of the wagon

body, several times across the wagon front between tackle blocks 24 and 25, thence around front guide sheave 29 on the wagon adjacent the lip of one of the doors, thence under sheaves 30 and 31 on the front and rear ends respectively of that door, thence over guide sheave 32 on the rear wall of the wagon body; thence under rear and front sheaves 33, 34 on the other door, and thence around guide sheave 35 to anchorage 36 at the front of the wagon. Any equivalent reeving may, however, be substituted.

From Figure 3, it will be seen that, when my cylinder is fully extended, so that the doors are closed, then the line of force between tackle blocks 24 and 25, i. e. the line between pivot 23 and pivot 16 is just below pivot 21, that is to say the linkage is just past toggle, and hence tension on rope 27, due to weight of the load on the doors, now tends to hold bellcrank 20 locked against the side wall of the wagon body, thus holding the door closed, and entirely relieving pressure on the cylinder. Not until fluid pressure in the cylinder is reversed so that the bellcrank is forced through toggle out of its locked position, can the doors be opened.

Thus we see that an effective mechanical lock is provided without any separate unlocking control and without adding any mechanical elements (since the bellcrank also serves as the support for one end of the cylinder assembly, i. e. the end that is connected to the movable tackle block).

Turning now to Figure 5, we see that as a second embodiment, I employ a single-acting cylinder 15a, modifying its connection to the bellcrank 20a so that when the doors are closed and bellcrank 20 is stopped against the wagon wall, the bellcrank is just short of toggle position so that most of the weight of the doors will be taken up by the bellcrank pivot and there will be very little pressure on the cylinder and leakage will be correspondingly small. The doors are then opened by merely releasing pressure fluid in the cylinder.

A few definitions, explanatory of the above. A "toggle linkage" concerns the relative position of three points. It comprises two hingedly connected links, actuating means to align and disalign the hinge point and the not-hinged end-points of the two links, and means actuated by the resulting alteration of the distance between the two not-hinged end-points to effect some desired result. For example, in both of applicant's variants (see particularly Figure 3), one link is that portion of the wagon-front extending from pivot 16 to pivot 21, and the other link is that portion of bellcrank 22 extending from pivot 21 to pivot 23, the hinge point is pivot 21, the two non-hinged end-points are pivots 16 and 23, the actuating means is cylinder-piston assembly 15-26, and the means actuated by alteration of the distance between points 16 and 23 is the rope 27.

When a toggle linkage is used as a lock, the three points are forced by the actuating means, from their unlocked out-of-toggle position (as shown dotted in Figure 3), into alignment (called "in toggle"), and then barely out of alignment beyond (called "just past toggle"; as shown in full lines in Figure 3), and there is means (in our case the contact between bellcrank 22 and the side-wall 11) to prevent any further disalignment of the three points. The tension or com-

pression in the actuated means (in our case, the tension in rope 27) holds the linkage locked in the just-past-toggle position, even though the actuating means be then released.

5 In my second variant, namely that of Figure 5, the three points approach complete alignment, but never attain it, being prevented by contact of the bellcrank with the side-wall; hence the extreme position attained may be called "just short of toggle."

10 It will be seen that the chief difference between my two variants is that in my first variant, when the control-mechanism is in door-closed position, its toggle-linkage is stopped just past toggle, and hence the actuating means has to be double-acting, but can be released when the linkage is locked just past toggle as above described; whereas in my second variant, when the control-mechanism is in door-closed position, its 15 control mechanism is stopped just short of toggle, and hence the actuating means can be single-acting, but must not be released so long as we desire to hold the door closed. These are the 20 relative advantages and disadvantages of my 25 two variants.

Having now described and illustrated two forms of my invention, I wish it to be understood that my invention is not to be limited to the specific forms or arrangements of parts hereinbefore described.

30 I claim:

1. In a bottom-dump vehicle, having a main dirt-containing body and an outwardly-opening bottom closure therefor, the combination of: a 35 lever pivoted on the main body; a sheave journaled on the lever at a point remote from the lever's pivot; a sheave journaled on the main body, the two sheaves being coplanar, and the lever being pivoted to swing in the plane of the 40 two sheaves; a rope trained about the sheaves, and operatively connected to the closure, and of such length as to hold the closure closed to the main body when the lever-pivot is aligned substantially in toggle between the two sheave- 45 axles; stop-means to limit the rotation of the lever with respect to the main body, the stop-means being so located as to engage when the lever-pivot and sheave-axes are substantially in toggle; and power means to swing the lever 50 into stop-means-engaging position.

2. A bottom-dump vehicle according to claim 1, further characterized by the fact that the stop-means-engaging position is just past toggle, and that the power means is double-acting.

55 3. A bottom-dump vehicle according to claim 1, further characterized by the fact that the stop-means-engaging position is just short of toggle, and that the power means is single-acting.

GEORGE W. MORK.
